UNITED STATES PATENT OFFICE.

MICHAEL J. SASGEN, OF CHICAGO, ILLINOIS, ASSIGNOR TO SASGEN DERRICK COMPANY, OF CHICAGO, ILLINOIS, A CORPORATION OF ILLINOIS.

DERRICK.

1,156,558.

Specification of Letters Patent.

Patented Oct. 12, 1915.

Application filed December 23, 1913. Serial No. 808,360.

To all whom it may concern:

Be it known that I, MICHAEL J. SASGEN, a citizen of the United States, residing at Chicago, in the county of Cook and State 5 of Illinois, have invented certain new and useful Improvements in Derricks, of which the following is a specification.

The derrick of the present invention relates to that type known as "the circle swing 10 portable derrick" used in building constructions mainly for the hoisting of the lighter materials, and adapted to be moved from floor to floor as the building is erected.

One of the objects of the present invention 15 is to produce a derrick of the above class which is simple and strong of construction.

Further objects of the present invention are to produce a derrick composed of but a 20 relatively few parts when the various characteristics which it possesses are taken into consideration; to provide a sheave-mounting on the outer end of the boom which will be arranged to simultaneously receive two 25 sheaves or sets of sheaves, thus eliminating the changing of booms when the derrick is changed from a hand-operated type to a power-operated type, or vice-versa; to provide an auxiliary sheave for use when the derrick is power-operated, which sheave will 30 be held in place by the same locking means that connect the boom with the member which joins it to the upper end of the mast; to produce a simple mounting for the drum, and to provide means for removing the 35 drum without disorganizing to any material extent the general arrangement of the derrick structure; to provide means for locking the mast to the base, and to utilize certain of these locking means as a hinge to enable 40 the mast to be swung down upon the base and into folded condition; to provide means for locking together the members which compose the base section, and to utilize this locking means as a hinge by means of which 45 one of the members of the base section can be swung into parallelism with the other, thus folding the base section; to make the derrick structure of a general knock-down type whereby it may be easily transported 50 from place to place as desired; and a further object resides in a novel method employed for joining the cable to the drum.

The invention further consists in the features of construction and combinations of parts hereinafter described and claimed.

In the drawings: Figure 1 is a side elevation of a derrick provided with the features of the present invention; Fig. 2 is a front view of the sheave-frame at the outer end of the boom; Fig. 3 is a front view of the 63 drum-mounting showing the same assembled in position to receive the drum; Fig. 4 is a side view of said mounting with the drum removed; Fig. 5 is a section through one of the journals for the drum; Fig. 6 is a plan 65 view showing the connection between the mast and the base, and the connection between the members composing the base section; Fig. 7 is a section showing the mounting for the auxiliary sheave; Fig. 8 is a face 70 view of a portion of the drum showing the means for attaching the cable thereto; and Fig. 9 is a cross section on line 9-9 of Fig. 8, looking in the direction of the arrows.

Referring to the drawings, and particularly to Fig. 1, the derrick is composed of three main sections, a base section 10, a mast 11, and a boom 12. The boom is of a triangular nature comprising a lower leg or rail 13, an upper leg or rail 14, and a 80 vertical tie or support 15 between said legs. The entire boom is, in the construction shown, made of metal, preferably angle iron, and attached to the outer end of the boom is a sheave-frame 16, which is formed, 85 in the construction shown, from a single casting or other metal structure. This sheave-frame serves as a mounting for a sheave or set of sheaves 17 which may be termed the "lower sheaves", and a sheave or 90 set of sheaves 18 which may be termed the "upper sheaves". Both of these sheaves find a mounting within this single frame, and are so arranged as to enable one of them to be actuated while the other remains idle 95 in position. This enables two sets of sheaves to be employed simultaneously, whereby the cable may be strung for operation of the derrick by hand or by power without changing the boom. It will be noted that the 100 sheaves do not extend in vertical parallelism one below the other, and they are so arranged as to enable one to operate without interference with the other.

The mast 11 is, in the construction shown, 105 formed of metal, and is of hollow formation. By this arrangement, the cable can be passed down through the mast whenever it is desired to operate the derrick by power from an engine located below, and an auxil- 110

5 iary sheave 19 is employed which is mounted within a frame 20, which frame is secured in place by locking members 21 that extend through the base of the frame and through a casting or other metal part 22, which 10 forms the connection between the boom and the upper end of the mast, and, therefore, this single set of locking members 21 serves the double function of locking the means in place which connect the boom with the upper end of the mast, and of locking the frame in place which carries the auxiliary sheave.

15 The connecting member 22 is composed of arms 23 which extend from a collar 24 which surrounds a pintle or end 25 on the upper end of the mast, which pintle is formed with or connected to a cap-piece 26. When the derrick is to be operated by hand-power, the cable is wound upon a drum 27 actuated 20 by a suitable crank 28. The drum is provided with trunnions 29 upon which are mounted a ratchet 30 and a disk 31, the ratchet being engaged by a pawl 32, and the disk 31 has its periphery engaged by a strap 33 forming in effect a band brake. This strap is actuated by a handle 34.

30 The mounting for the drum consists of companion plate-like members 35 which are arranged to lie upon opposite sides of the lower leg 13 of the boom 12. One of these plates is provided with lugs or bosses 36 and 37, the lug 36 forming a mounting for the pawl 32, and the lug 37 forming a mounting 35 for the brake handle 34.

40 Each of the plates is formed with a U-shaped slot 38 into which slot is inserted the trunnion 29 of the drum, together with a collar 39 of anti-friction bearing material, which surrounds the trunnion, and the trunnion, together with the bearing, are held in place by means of a block-like member 40 which is inserted into the open lower end of the slot 38, and is held in place by suitable locking members as bolts 41. By 45 this arrangement, a support and mounting for the drum is provided which is extremely cheap of manufacture, and which receives and maintains the trunnion of the drum in a manner whereby the dismantling of the drum is rendered simple and easy, and made possible without a disassemblance of any material number of parts of the device.

50 A casting or other metal part 42 is provided with which the plates 35 are formed or secured, and said casting consists of a semi-cylindrical portion 43, from which extend arms 44, and these arms are arranged to lie upon opposite sides of the leg 13 of the boom 12. Locking members 45 are provided which serve to hold the casting and drum-mounting in place.

55 The semi-cylindrical portion 43 of the casting 42 is seated within a flanged collar 46, and this collar also receives a semi-circu-

lar casting or metal part 47 which, in conjunction with the semi-circular portion of the casting 42, forms a split ring which lies within the flanged collar 46. The semi-cylindrical portion of the casting 42 has 70 extending therefrom a lug or thumb 48 which extends through a flange 49 on the semi-cylindrical member 47, and to this thumb 48 is eccentrically pivoted a locking member 50, by the operation of which the parts composing the split ring are drawn into engagement with, or released from engagement with, the flanged collar 46, thereby locking the boom against revolution about the mast, or permitting the boom to 80 swing about the mast as may be desired.

85 Suitable struts 51 are provided for reinforcing the mast. The mast at its lower end has secured thereto a member 52 which extends about the lower end of the mast, as shown in Fig. 1, and is held thereon by suitable locking members. This member 52 is provided with a set of ears 53 and a set of ears 54 arranged to lie upon opposite sides of the mast, as shown more clearly in 90 Fig. 6. The base section is composed of a member 55 and a member 56 lying, as shown in Fig. 6, at right angles to one another when the derrick is in use. Attached to the member 55 is a casting 57 secured thereto 95 by suitable locking means 58. The upper face of this casting is provided with a set of ears 59 and a set of ears 60, the ears 59 being arranged to align with the ears 54 when the mast is placed upon the base, and 100 the ears 60 with the ears 53 when the mast is so positioned.

105 A locking member 61 passes through the ears 60 and 53, each of which ears are provided with an aligned opening to permit such passage of the locking member, and each of the ears 54 and 59 is also provided with an aligned opening, whereby a locking member 62 can be inserted through these ears. When the derrick is in operation, the locking members 61 and 62 serve to maintain the mast in rigid position as respects the base. When, however, the derrick is to be transported, the locking member 61 may be removed, and then the locking member 62 110 will act as a pivot or hinge, whereby the mast may be laid downward upon, and on top of, the base member 55, thus folding this portion of the device in compact form. Prior to this operation, the boom 12 may be 115 removed, which can be very easily done by removing the connection between the members 47 and 42 composing the split ring. As will be obvious, after removing this connection the boom can be lifted upward until 120 the collar 24 is removed from the pintle 25. The struts 51 are connected to the base by any suitable releasable locking means as a bolt 51^a, and when it is disconnected may be folded about the pin or other connection 130

63, and thus the boom and mast can be arranged to lie in a very compact condition.

The members 55 and 56 comprising the base section, as stated, normally lie at right angles to one another and are joined together and held in such normal relation by means of locking members 64 and 64^a passing through ears 65 on the casting 57 and through ears 66 on a casting or other metal part 67, which latter casting is secured to the member 56 by suitable bolts or locking members 68. When the locking members 64 and 64^a are both in position, the members 55 and 56 are maintained at right angles to one another, and this is the position they assume when the derrick is in operation, but should the locking member 64 be removed, then the locking member 64^a will serve as a hinge or pivot about 20 which the member 56 can be swung to place it in the position shown in dotted lines in Fig. 6, or in a position whereby it extends parallel with the member 55 in place of at right angles to said member, and this enables the base section to be folded into compact form for transportation purposes.

The drum 69, as shown in Figs. 8 and 9, is provided with flanges 70, and adjacent to one of these flanges is a slot or opening 71 comprising an enlarged portion 72 and a reduced portion 73, and in the construction shown is similar to a button-hole slot. At the juncture of the enlarged and reduced portions of said slot is a lip 74. The end 35 of the cable is initially inserted within the enlarged portion, as shown in Fig. 8, and is then driven down into the small portion, as shown in Fig. 9, whereby it is compressed and securely held within the slot; then by 40 tapping the lip 74 with a hammer or other instrument, the opening 75 between the enlarged and reduced portions of the slot may be contracted, thus firmly securing the cable in place. When it is desired to remove the cable, it is driven out from the reduced portion of the slot and into the enlarged portion. This provides a means 45 for attaching the cable to the drum, which is simple and which permits of the ready removal, or connecting of the cable from or with the drum, as the occasion demands.

From the foregoing, it will be seen that the entire derrick can be quickly and easily folded into position for transportation and 55 can be quickly and easily reassembled in operative position when desired.

The structure above described with particularity is, of course, subject to variations in construction, and it is not the intention 60 to limit the scope of the present invention other than by the terms of the appended claims.

I claim:

1. In a derrick, the combination of a base, 65 a mast extending from the base, a boom ex-

tending from the mast, a freely detachable connection between the boom and mast, companion horizontally disposed removable members lying at opposite sides of the mast for locking the mast to the base, said members extending in the same direction, one of said locking members serving, when the other locking member is removed, as a pivot about which the mast is swung into folded condition upon the base, substantially as 75 described.

2. In a derrick, the combination of a base, a mast extending from the base, a boom extending from the mast, a freely detachable connection between the boom and mast, 80 companion sets of ears on the base, companion sets of ears on the lower end of the mast, said latter ears being arranged to align with the ears on the base and a horizontally disposed removable locking member passing 85 through each aligned set of ears, said members extending in the same direction, one of said locking members serving, when the other locking member is removed, as a pivot about which the mast is swung into folded 90 condition upon the base, substantially as described.

3. In a derrick, the combination of a base, a mast extending from the base, a boom extending from the mast, said base comprising 95 members arranged at right angles to one another and companion oppositely disposed parallelly extending members arranged at the juncture of the base, members for locking said base members together, one of said 100 locking members serving, when the other locking member is removed, as a pivot about which one of said base members is swung into parallel relation with the other base member, substantially as described. 105

4. In a derrick, the combination of a base, a mast extending from the base, a boom extending from the mast, said base comprising right angled members, an end piece on each of said base members, each of said end 110 pieces being formed with oppositely disposed apertured ears, the ears on one member being arranged to align with the ears on the other member when said members are in angled relation, and a removable member passing through the apertures of each set of aligned ears and acting as locking members, one of said locking members serving, when the other locking member is removed, as a pivot about which one of said 115 base members is swung into parallel relation with the other base member, substantially as described.

5. In a derrick, the combination of a mast having a longitudinal bore therethrough, a 125 boom extending from the mast, a drum lying on the under side of the boom, a sheave frame on the outer end of the boom, said frame being arranged to simultaneously receive a lower and upper sheave, said lower 130

sheave being adapted to receive a cable passing to the drum, and said upper sheave being adapted to receive a cable passing to the bore in the mast, substantially as described.

6. In a derrick, the combination of a mast, a boom extending from the mast, a flanged collar secured to the mast intermediate the ends of the mast, a drum, a mounting for the drum formed of a single piece of metal embodying companion plates joined together by a semi-circular web arranged to fit the collar, said web extending in a horizontal plane and the body of the plate extending

in a diagonal direction upward from said web in correspondence to the angle in which the lower rail of the boom is placed, a semi-circular ring arranged to fit the collar, and a connection between the web and ring to draw the same against and release the same from engagement with the collar whereby a lock for the boom is provided, substantially as described.

MICHAEL J. SASGEN.
